CLAIM

The ornamental design for a port replicator for extending the functions of a portable personal computer, as shown and described.

DESCRIPTION

FIG. 1 is a front perspective view of the port replicator for extending the functions of a portable personal computer showing my new design with a portable computer being shown in broken lines for illustrative purposes only and forming no part of the claimed design;

FIG. 2 is an enlarged rear perspective view of the port replicator shown in FIG. 1 with the connector and accessory end being illustrated and the accessories being shown in broken lines for illustrative purposes only and forming no part of the claimed design;

FIG. 3 is a front elevational view of the port replicator shown in FIG. 1;

FIG. 4 is a rear elevational view of the port replicator shown in FIG. 1;

FIG. 5 is a side elevational view of one side of the port replicator illustrated in FIG. 1;

FIG. 6 is a side elevational view of the port replicator illustrated in FIG. 1;

FIG. 7 is a top plan view of the port replicator illustrated in FIG. 1; and,

FIG. 8 is a bottom plan view of the port replicator illustrated in FIG. 1.
